UNITED STATES PATENT OFFICE.

SELIM A. KATIBAH, OF NEW YORK, N. Y.

DESIGN FOR A LAVALLIÈRE.

47,520.

Specification for Design.

Patented June 29, 1915.

Application filed March 1, 1915. Serial No. 11,428. Term of patent $3\frac{1}{2}$ years.

To all whom it may concern:

Be it known that I, SELIM A. KATIBAH, a subject of the Sultan of Turkey, a resident of Syria, and residing in the borough of Brooklyn, county of Kings, city and State of New York, have invented a new, original, and ornamental Design for a Lavallière, of which the following is a specification.

Reference is to be had to the accompanying drawing for a full disclosure of my design, in which:

Copies of this patent may be obtained for five cents each, by addressing the "Commissioner of Patents, Washington, D. C."

I claim:

The ornamental design for a lavallière as shown.

In witness whereof I have hereunto set my hand at the borough of Manhattan, city and State of New York, this 27th day of February, 1915.

SELIM A. KATIBAH.
